ELECTRICAL MUSICAL INSTRUMENT

John M. Hanert, Wilmette, Ill., assignor to Hammon Instrument Company, Chicago, Ill., a corporation of Delaware

Application September 14, 1942, Serial No. 458,305

7 Claims. (Cl. 84—1.21)

1

My invention relates generally to electrical musical instruments and more particularly to improved duplex melody instruments upon which two notes may be played simultaneously.

The invention is of peculiar utility when used as a substitute for, or as a supplement to, the bass or pedal clavier section of a pipe organ, or any other type of organ. The pipes for the bass section of a pipe organ are the largest and most expensive in the organ and, as a result, even the largest pipe organs are considerably limited as to possible tonal variation in their bass sections.

It is therefore an object of the invention to provide an improved means for producing the bass tones of an organ.

A further object is to provide an improved frequency generating system for electrical musical instruments, utilizing the principle of frequency division.

A further object is to provide an improved melody type of instrument having a keyboard, an electrical tone frequency generating system, and output system, which is effective to sound the tones corresponding to any two keys which may be simultaneously depressed, or to sound the highest and lowest of any three or more keys which may be simultaneously depressed.

Other objects will appear from the following description, reference being had to the accompanying drawings in which:

Figure 1 is a wiring diagram of the keyboard and a portion of the frequency generating system of the instrument;

Figure 1a is the wiring diagram of the circuits for frequency division, tone quality controlling, and for amplifying the signal and translating it into sound; and

Figures 2, 3 and 4 are schematic wiring diagrams of modified forms of dividing circuits.

The invention may be utilized for the production of tones in any desired frequency range, but has particular utility when used as the bass section of an organ, and the invention is therefore described herein as embodied in such form.

Referring to Figure 1, the instrument is illustrated as comprising a pedalboard of the usual range of 32 notes extending from the low note C0 (32.703 C. P. S.) to the higher note G2 (196.00 C. P. S.). The keys bear reference characters corresponding to the pitches of the tones ordinarily produced upon depression thereof.

Each of the keys C0 to G2 is provided with an actuator, indicated by a dotted line in the drawing, for operating two switches 10 and 11. The switches 10 are resiliently biased so as each nor-

2

mally to be in contact with a fixed contact 12, and are adapted when the associated key is depressed to break the contact with the contact 12 and to make contact with a fixed contact 14.

Similarly, the switches 11 are normally in engagement with contacts 13 and are adapted, when the key is depressed, to engage fixed contacts 15. It will be noted that the switch arms 10 are in series and that the contact 12 for the key C0 is connected to ground, while the switch arm 10 for the highest key G2 is connected to a conductor 16. The contacts 14 are connected to taps of an inductance winding L2 which is in inductive relation with a feedback winding L4.

In a similar manner the switches 11 are connected in series and normally engage their contacts 13. The contacts 15 of these switches are connected to taps of a tuning inductance L3 which is in inductive relation with a feedback winding L5. The ends of the inductances L2 and L3 beyond the key G2 are grounded. The switch 11 for the key C0 is connected to a conductor 17.

The inductances L2 and L3 form parts of oscillators which include respectively triodes 20 and 21. The triode 20 comprises a cathode 22, a grid 24 and a plate 26, while the triode 21 includes a cathode 23, a grid 25 and a plate or anode 27. The conductor 16 is connected to the grid 24 through a grid bias resistor R2, by-passed by condenser C2, and is connected to ground through a tuning condenser C4. Similarly, the conductor 17 is connected to the grid 25 through a grid resistor R3, by-passed by condenser C3, and is connected to ground through a tuning condenser C5.

Plate current is supplied to the triode 20 through a load resistor R4 connected to the plate 26 from a suitable source of direct current potential indicated by a terminal +300 v. Similarly, plate current for the triode 21 is supplied through a load resistor R5. The cathodes 22 and 23 are respectively connected to ground through the properly phased feedback windings L4 and L5.

From the foregoing it will appear that if any single key is depressed, predetermined proportions of the inductances L2 and L3 will be rendered effective in the tuning circuits for the oscillator tubes 20 and 21 respectively, and that when two or more of the keys C0 to G2 are simultaneously depressed, the highest of these depressed keys will, through the closure of its switch 10, tune the oscillator tube 20 to the pitch represented by such key, while the lowermost of such depressed keys will tune the oscillator tube 21 to the pitch represented by such key. When three

or more keys are simultaneously depressed, depression of the intermediate keys has no effect upon the tuning of the oscillators.

The output signal of the oscillator 20 is transmitted through a blocking condenser C6 to a conductor 28, while the output signal of the oscillator 21 is transmitted through a blocking condenser C7 to a conductor 29.

A non-linearly operating pentode 30 has its cathode 32 connected to ground through a biasing resistor R6, and its grid 34 connected to the conductor 28 through a series grid resistor R8, the conductor 28 being connected to ground through a grid resistor R10. The screen grid 36 of the pentode 30 is connected to a suitable source of direct current potential indicated as a terminal +125 v., while the suppressor grid 38 is connected to the cathode 32. The plate 40 is connected to a suitable source of plate potential indicated as a terminal +300 v. through a load resistor R12, and is connected to a conductor 42 through a blocking and charging condenser C8.

The oscillator 20 may have a distorted half wave rectifier type wave shape output, but the pentode 30 is biased so as to convert this wave into a generally rectangularly shaped wave, since the negative portion of the input wave is cut off by virtue of the negative grid bias, while the positive portion of the input wave is cut off due to the change in the input impedance of the grid circuit of the pentode. A pentode of the 6J7G type operates satisfactorily for this purpose.

A pair of diodes 44, 46, which may be of the 6H6 type, are provided to rectify the output of the pentode 30. For this purpose the cathode of diode 44 is connected to the conductor 42 while its plate is connected to ground and the diode 44 will therefore conduct to ground the negative portion of the output wave of the pentode 30. The diode 46, however, has its plate connected to the conductor 42, while its cathode is connected to a terminal 47 which is connected to the plate 48 of a triode 50. The cathode 52 of the triode 50 is connected to ground while its grid 54 is connected through a current limiting resistor R14 and a tertiary winding L6 with a suitable source of biasing potential indicated as a terminal -7 v.

A charge accumulating and blocking condenser C10 has one terminal connected to the terminal 47, while its other terminal is connected to ground through a primary winding L8 of a transformer T2, the winding L8 having a plate load resistor R16 connected in parallel therewith. The condenser C10 has a value large with respect to that of the condenser C8, its value being determined by the number by which division of the output frequency of the pentode 30 is desired. As utilized in the embodiment of the invention disclosed, the condenser C10 will be chosen to have such value that two positive pulses through the diode 46 will be required to charge the condenser C10 to a sufficiently high value that plate current will flow in the triode 50 despite its substantial negative bias. The triode 50 may be of the 6J5G type.

The transformer winding L8 is so phased with respect to the winding L6 that as the plate current commences flowing through the triode 50, the bias on the grid 54 will be less (i. e., its potential will be raised to a less negative value than its normal -7 v. biasing potential), and as a result, as soon as any plate current commences flowing through the triode 50, the rate of flow will increase rapidly until the charge on the con-

denser C10 has been reduced to value such that further increase in the potential of the grid does not cause a corresponding increase in plate current. During the time that the plate current flow through the triode 50 is decreasing, the inductance L6 will of course be effective to increase the grid bias at an accelerating rate so that the bias on the triode 50 will rapidly return to a value beyond cut off. As a result, the signal across the winding L8 will be a sharply peaked wave.

A secondary winding L10 of the transformer T2 is connected to a second non-linear pentode 56 which operates in a manner identical with that of the pentode 30. The elements connected to the pentode 56 are likewise substantially identical with those associated with the pentode 32. The output of the pentode 56 is connected through the blocking and charging condenser C12 with a conductor 60, and the latter is connected to the cathode and plate respectively of diodes 62, 64, the plate of the tube 62 being grounded and the cathode of tube 64 being connected to a terminal 66. The terminal 66 is connected to the plate of a triode 70 which may be identical with the triode 50 and have similar circuit elements associated therewith. A blocking and charge accumulating condenser C14 corresponds to the condenser C10 associated with the triode 50. The output of the triode 70 is transmitted to a terminal 72 through the secondary winding L12 of a coupling and feedback transformer T4. One end of the secondary winding L12 is grounded, while the other end is connected to the terminal 72 through a decoupling resistor R18.

As previously pointed out, the signal supplied by the oscillator 20 has its frequency divided by "2" by virtue of the first frequency dividing stage which includes the pentode 30, diodes 44, 46 and triode 50. In a similar way the pentode 56, diodes 62, 64 and triode 70 and their associated circuit elements constitute a second frequency dividing stage, dividing the frequency of the output of the first stage by "2," so that the frequency of the signal across the secondary winding L12 will be one fourth of that of the oscillator 20.

Means are provided to successively divide the frequency of the output of the oscillator 21 by the factor of 2, the first stage of such frequency divider system including a pentode 31, diodes 45, 47, triode 51 and associated circuit elements similar to those previously described. The second stage of frequency division includes a pentode 57, diodes 63 and 65 and triode 71, the first stage being coupled to the second stage through a transformer T3 and the output of the second stage being coupled to the terminal 72 through a transformer T5, the second winding L13 of which has one terminal connected to ground and the other terminal connected to the terminal 72 through a decoupling resistor R19.

Since these frequency division stages are essentially identical, the foregoing description of the stage which includes the non-linearly amplifying pentode 30 will suffice for an understanding of the construction and operation of the other stages, it being noted that the input of the first stage which includes the non-linear amplifying pentode 31 is connected to the conductor 29, thus to receive a signal from the oscillator 21.

The terminal 72 is connected to the grid 80 of a linearly amplifying pentode 82, the cathode and suppressor grid of which are connected to ground, the screen grid 84 connected to a terminal +125 v., and the plate 86 connected through a load resistor R20 to a terminal +300 v. A grid

resistor **R21** is connected between the grid **80** and a suitable terminal for supplying the negative grid bias.

Connected in parallel with the load resistor **R20** (i. e., between the plate **86** and a terminal **+300 v.**, is a series of filtering meshes **88, 89, 90** and **91**, which are adapted to be selectively rendered effective upon the opening of one or more of a plurality of switches **92**.

The plate **86** of the pentode **82** is also connected through a decoupling resistor **R22** with a conductor **94**, the latter providing the input, through a blocking condenser **C18**, for an amplifier **96**. The output of the amplifier **96** is supplied to the speaker **98** and has an intensity or volume control means **100** associated therewith.

A linearly amplifying pentode **102** has its grid **104** connected to the ungrounded terminal of the secondary **L10** through a decoupling resistor **R24** as well as being connected through a decoupling resistor **R25** with the ungrounded terminal of the secondary winding **L11** of the transformer **T3**. The grid **104** is also connected to a suitable operating bias potential through a grid resistor **R27**. The output of the amplifying pentode **102** is adapted to be modified by filtering meshes **106, 107, 108** and **109** upon selective opening of one or more control switches **110** in a manner similar to that described with the generally corresponding output circuit of the pentode **82**. The output of the pentode **102** is impressed upon the conductor **94** through a decoupling resistor **R26**.

A linearly amplifying pentode **112** has its grid **114** connected to conductors **28** and **29**, decoupling resistors **R28** and **R29** respectively, and is supplied with a suitable operating bias through a grid resistor **R31**. The output circuit of the pentode **112** includes a series of filtering meshes **116, 117, 118** and **119** adapted to be selectively rendered effective by opening one or more of a plurality of switches **122**. The output of the pentode **112** is also coupled to the conductor **94** through a decoupling resistor **R30**. The pentodes **112** and **102**, and their associated circuit elements, are essentially identical and for this reason these parts have not been described in detail.

In using the instrument, it is played in the manner of a conventional organ pedal clavier with the exception, however, that the instrument will be capable of playing only two notes simultaneously. It is only upon extremely rare occasions in organ literature that the score calls for playing more than two pedal notes simultaneously, and even on such rare occasions the organist seldom follows the score because of the difficulty of execution. Thus, the pedal clavier instrument of this invention is, for all practical purposes, played in a manner exactly the same as any polyphonic organ pedal clavier.

As previously pointed out, the depression of any pedal results in connecting a predetermined portion of the inductance **L2** into the tuning circuit of the oscillator **20**, and in doing so, the switches **10** of all lower keys are disconnected and thus rendered ineffective. Similarly, the depression of such key causes the connection of a predetermined portion of the inductance **L3** in the tuning circuit for the oscillator **21**, and disconnects the switches **11** of keys corresponding to higher pitches from the tuning circuit so that thereafter depression has no effect upon the tuning of the oscillator. Thus, the oscillator **20** will be tuned to the highest of any of a plurality of simultaneously depressed pedals, while the oscillator **21** will be tuned to the lowest of any of

such plurality of depressed keys. If only one key is depressed, both oscillators will be tuned to the same frequency.

It will be noted that the inductances **L2** and **L3** are variable for initially tuning the oscillators, such variation being preferably effected by adjusting the air gaps in the cores of these coils. This tuning may be done initially in the course of production of the instrument, and will ordinarily not require readjustment for long periods of time.

As previously pointed out, the signals from the oscillators **20** and **21**, tuned to the desired frequencies by the depression of one or two pedals, have their amplitude held constant by the amplitude limiting tubes **30** and **31** respectively. Thus, the output waves of these tubes are of uniform amplitude irrespective of variations in the frequency or amplitude of the signals impressed upon their grids. Because of this function of the tubes **30** and **31**, the dividing system is rendered extremely stable.

Thus, the diodes **44, 46** and **45, 47** are supplied with signals of constant amplitude, and due to the non-linearity of the tubes **30, 31**, the wave shapes of these signals will have very steep wave fronts. The capacity of the condenser **C10** relative to the capacity of the condenser **C8** is so chosen that the potential across the condenser **C10** will build up to a value sufficient to cause the plate current to flow through the triode **50** when either 2, 3, 4 or any reasonably large integral number of impulses have been supplied to the condenser **C10**. Although the operation of the circuits associated with the tubes **30** and **50** has been described as producing a frequency division by using 2 as the divisor, sub-multiples of the input frequency using other integers of 3 and higher as divisors may be employed. This divider circuit may be used to divide the frequency by divisors running up into the thousands, and its division will be mathematically exact, depending upon the stability of the circuit elements. Using circuit elements of commercial tolerances, mathematically accurate divisions by a factor of 10 may easily be obtained, and division by higher divisors may be obtained within relatively small percentage variations from mathematically exact frequency division.

Assuming, as initially described, that division of the stage including the tubes **30, 50** and **31, 51** is by a factor of 2, the output of these stages will be an octave lower than the input frequency, and in the stages including the tubes **56, 70** and **57, 71**, assuming again a division using 2 as a divisor, the resulting quotient frequency appearing across the windings **L12** and **L13** will be two octaves below the frequencies generated by the oscillators **20** and **21**. Thus, by operating the various stops represented by the switches **92, 110** and **122**, various octavely related tones may be produced. In organ nomenclature, the switches **92** correspond to the **16'** stops of the pedal division, while the switches **110** correspond to the **8'** stops of the pedal division and the switches **122** correspond to the **4'** stops of the pedal division. By operating the switches of these several groups in various combinations, complex pedal tones consisting of octavely related tone qualities may be produced.

While the invention has been described as applied to the production of the tones controlled by a pedalboard, it will be clear to those skilled in the art that by suitable changes in the circuit elements the register of the instrument may be

changed. For example, one of the oscillators 20, 21 together with a series of cascaded stages of frequency division might be utilized as the frequency generating apparatus for instruments of the types shown in Hammond et al. Patent No. 2,233,258 or in my prior Patent No. 2,254,284.

The dividing circuit of the invention is particularly adapted for division of frequency of a variable frequency oscillator or other variable frequency source because it is extremely stable throughout a wide range of the input frequency. Thus, substantial changes in the input frequency do not in any way impair the stability of the dividing stages. The reason for this is that each change that occurs in either voltage or current in the circuit elements which are connected together to form the divider system is initiated solely by the presence of a signal pulse transmitted by condenser C8 to a divider system. For example, the charge on condenser C10 increases by discreet increments, each increment of voltage being a reflection of a change in input conditions on the grid 34 of tube 30, which is supplied by the signal source. Thus, the amplitude at which the tube 50 discharges is a function of the number of times that condenser C8 has charged condenser C10 and is not a function of the absolute frequency generated by the oscillators 20 or 21.

In this respect this frequency divider differs in operation from relaxing dividers, from multivibrators, blocking oscillators, etc. In these latter types of frequency controlled devices there are change in polarity, voltage, and current in the elements of the oscillator system which change, not because of the presence of a controlling signal, but because of their own time constant functions, e. g., the charging of a relaxation condenser through a charging resistance after said condenser has been discharged by a gaseous discharge tube having a grid which was operated positively by a controlling input signal. In the latter exemplary case the controlling signal operates to cause the discharge of the condenser, but the rate of charging of the condenser is determined by constants of the circuit elements associated with the condenser, and the rate is such that frequency division by some factor would occur for a given input frequency. Thus, this type of frequency divider divides certain frequencies only, whereas the frequency divided of this invention divides all frequencies over an extremely wide audio frequency spectrum. There are no time constant elements in the frequency divider which are in any way comparable in time to the period of the frequency being divided. All potential changes in the operation of the divider circuit of this invention are signal controlled.

This non-linear, non-time constant frequency dividing principle of the invention may be embodied in other forms such as illustrated in Figs. 2, 3, and 4.

In the circuit of Fig. 2, a source 130 of variable frequency supplies impulses through a condenser C8, conductor 42 and rectifier diodes 44 and 46 to a condenser C10, in the same manner as previously described with reference to Fig. 1a. In this circuit, however, the charge on the condenser C10 affects the voltage at the plate 132 of a Thyratron type of gaseous discharge tube 134, which may be, for example, of the 885 type. The condenser C10 is coupled to the plate 132 through a small inductance L16 and protective resistor R36. The grid 136 of tube 134 is connected to a biasing voltage source, indicated as a terminal

-9 v., through a protective resistor R37, but the grid is not utilized for control purposes, the 885 type tube being utilized merely as a gas discharge diode tube. A cold cathode gas diode might be substituted for the Thyratron 134, but the latter is preferred because of its high degree of stability. In the case of the Thyratron 134, the heated cathode 138 thereof is connected to ground, and the positive signal from the rectifier diode 46 is impressed upon the plate 132. If, however, a cold cathode diode is used in place of the Thyratron 134, either the positive or negative pulse from the rectifier tubes 44, 46 may be impressed upon one plate of the diode.

As soon as the condenser C10 has accumulated a sufficient potential to cause ignition of the Thyratron 134, the latter will discharge the condenser C10 substantially to ground potential. The signal thus produced in the primary 140 of an output transformer T6 may be utilized to provide a signal one half that of the source 130 to a conductor 142, and may also be utilized as an input for an amplitude limiting pentode 56 of a second frequency dividing stage.

In principle, the operation of the circuit of Fig. 2 is the same as that shown in Fig. 1a, since the condenser C10 is incrementally charged through the condenser C8 to a value such that it causes an amplitude responsive discharge apparatus, in the form of the Thyratron 134, to function. It will be noted that in the circuit of Fig. 2, just as in Fig. 1a, there are not circuit elements associated with the Thyratron 134, which provide a time constant comparable to the period of the signal. Thus, this gaseous discharge frequency divider is unlike the usual gaseous discharge relaxing oscillator type frequency divider in that all circuit functions are initiated solely by the signal, and thus the controlling frequency plays no part in the frequency division ratio.

In Fig. 3, the circuit includes the variable frequency source 130 and rectifying circuits similar to those of Figs 1a and 2. The positive pulses of the rectified input signal are thus accumulated on the condenser C10, one terminal of which is connected to the plate 142 of a triode 144, such for example, as the 6J5G type. The grid 146 of the triode 144 is connected through a series grid resistor R40 and a grid resistor R41 to a source of biasing potential indicated as a terminal 147. The cathode 148 of the triode 144 is connected to ground. The output of the triode 144 is coupled through a condenser C12 to the grid 150 of a triode 152, the grid 150 being connected to a suitable biasing potential source through a grid resistor R42. The plate 154 of the triode 152 is connected to a suitable source of plate voltage indicated as a terminal +300 v. through a load resistor R44. The plate 154 is also connected through a feedback condenser C14 to a terminal 149 intermediate the resistors R40 and R41. The output of the triode 152 is coupled through a blocking condenser C16 to the input of a current limiting pentode 56 corresponding to the tube 56 in the previously described circuits.

The circuit of Fig. 3 operates to divide the frequency of the source 130 in the following manner: As the condenser C10 attains a charge sufficient to cause the triode 144 to start to conduct plate current, such conduction is rapidly increased to effect a substantial discharge of condenser C10 by virtue of the fact that tube 152 serves as a phase inverter to provide a signal of positive polarity through feedback condenser

C14 to the grid 146, thus increasing the plate current of tube 144 until condenser C10 is discharged and further increase in positiveness of the grid 146 has no effect. In practice, this discharge takes place in an extremely short space of time compared to the frequency of the source 130. Thus, the circuit of Fig. 3 corresponds to that of Fig. 1a, it being noted, however, that the phase inversion in the grid circuit is accomplished through the triode 152 in the circuit of Fig. 3, whereas in the circuit of Fig. 1, this phase inversion is accomplished through the use of the tertiary winding L3 of the transformer T2.

A further modified form of frequency dividing circuit which does not have any frequency resonant or timing constants associated therewith, but which instead has its operation controlled solely by the application of impulse of the frequency to be divided, is shown in Fig. 4. In this figure a pair of Thyratrons 160, 161, have their grids 162, 163 connected to the source 130 through blocking and decoupling condensers C18 and C19 respectively. The grids 162, 163 are connected to a suitable source of biasing potential indicated as a terminal -17 v. through grid resistors R50 and R51 respectively. Protective resistors R52 and R53 may be provided for the grids 162 and 163.

The plates 166 and 167 of the Thyratrons 160 and 161 are respectively connected to a suitable plate current potential source indicated as terminals +170 v. through load resistors R54 and R55, as well as through low value protective resistors R56 and R57 respectively. The plates 166 and 167 are coupled through a relatively large condenser C20. The cathode 168 of the Thyratron 160 may be connected to ground, while the cathode 169 of the Thyratron 161 may be connected to ground through a resistor R50 across which an output signal may be derived through a blocking condenser C21, such signal being impressed upon the grid of a limiting pentode 56, operating as previously described.

In the operation of the dividing circuit of Fig. 4, a signal pulse from the source 130 is simultaneously impressed upon the grids 162 and 163. However, due to unavoidable differences in the parameters of these tubes and the circuit elements associated therewith, only one of these tubes is rendered conductive, and the other tube is immediately prevented from reaching a discharge condition because of the following factors. Assume that upon impressing a positive pulse from the source 130 upon the grids of these tubes, the gas of the tube 160 ionizes. The resultant plate current flow in this tube lowers the potential at the junction 170, and hence upon the junction 171, sufficiently to lower the potential on the plate 167 below the ignition point for a period of time in excess of the deionization time, but still small by comparison with the period of the frequency being divided. Thus, if the tube 161 was ionized at the time that the positive impulse was impressed upon its grid, it will be deionized.

Such conditions will continue until the next positive pulse from the source 130 finds the grid 162 in an already ionized gaseous discharge path between the cathode 168 and plate 166, and thus has no control. However, the pulse impressed upon the grid 163 is effective to cause ionization to occur in the tube 161 and thus lowers the potential at the point 171, and correspondingly the potential at the point 170, to the deionization point of the tube 160. This cycle is repeated with each alternate positive pulse from the source 75

130, and as a result, the signal across the resistor R60, which is of generally square wave shape, will have a frequency one half that of the source 130.

5 It will be noted that this output or quotient frequency is not dependent upon any time constants of the elements associated with these tubes 160, 161, and that the alternate discharge of the tubes 160 and 161 is controlled solely by the application of the controlling signal from the source 130. Thus, this apparatus is effective to divide the frequency of the source 130 over a very substantial range of the audio frequency spectrum, such as 4 or 5 octaves.

15 The divider circuit of Fig. 4 differs from those of Figs. 1a, 2 and 3 in that it is capable of division only by the factor of 2, whereas the circuits of Figs. 1a, 2 and 3 are capable of dividing by any integral divisor factor. However, all of the divider circuits disclosed herein have the distinguishing feature that all of their voltage, current, and polarity changes respond only upon the application of a controlling signal, which is not the case, for instance, of controlled relaxation devices or the like.

20 25 While I have shown and described a particular embodiment of my invention it will be apparent to those skilled in the art that numerous modifications and variations may be made in the form and construction thereof, without departing from the more fundamental principles of the invention. I therefore desire, by the following claims, to include within the scope of my invention all such similar and modified forms of the apparatus disclosed, by which substantially the results of the invention may be obtained by substantially the same or equivalent means.

I claim:

30 35 40 45 50 55 60 65 1. In an electrical musical instrument having an output system including electroacoustic translating means, the combination of an electrical pulse signal generator of "dividend" frequency, a plurality of playing keys, means operable by said keys for selectively tuning said generator to an audio frequency related to the nominal pitch corresponding to the operated key, a frequency dividing circuit containing a negative reactance frequency divider element, a non-linear electron discharge device coupled to said negative reactance element, a coupling between said pulse generator and said electron discharge device such that all potential changes and polarity reversals on said frequency dividing negative reactive element are initiated solely by the application of said signal, said frequency dividing circuit thereby producing a "quotient" frequency related to said "dividend" frequency by an integral divisor, said divisor remaining a constant over a wide audio frequency spectrum exceeding one octave of "dividend" input frequency, signal collecting means for said pulse signal generator, signal collecting means for said frequency dividing means, and selectively operable means coupling either or both of said signal collecting means to the output system of the instrument.

70 75 80 85 90 95 2. In an electrical musical instrument having an output system including electroacoustic translating means, an adjustable frequency oscillator, key actuated means for determining the frequency at which said oscillator operates, means coupled to the oscillator and controlled solely by the number of electrical impulses produced by said oscillator to produce a rectangular wave impulse for every second impulse provided by said oscillator, and a tone quality controlling trans-

11

mission circuit coupling said means to the output system of the instrument.

3. In an electrical musical instrument having an output system including electroacoustic translating means, the combination of a source of electrical impulses of variable frequency, playing keys operable to determine the frequency of the impulses derived from said source, means to convert said impulses into electrical pulses of uniform amplitude, means to accumulate said pulses, electrical discharge means responsive to the accumulation of a predetermined number of said pulses by said last named means to cause the discharge thereof, and means coupling said discharge means to said output system.

4. In an electrical musical instrument having an output system including electroacoustic translating means, a variable frequency source of electrical impulses of uniform amplitude, a plurality of playing keys, means operable by said keys to vary the frequency of said source, means for accumulating the electrical charges of said impulses, a device responsive solely to the total charge on said accumulating means to cause rapid discharge thereof, and means for coupling said device to the output system of the instrument.

5. In an electrical musical instrument having an output system including electroacoustic translating means and having a pedalboard comprising a plurality of keys, the combination of a pair of oscillators, circuits completed upon depression of two or more of said keys to tune one of said oscillators to a frequency related to the pitch corresponding to the lowest of the depressed keys and to tune the other of said oscillators to a frequency related to the pitch corresponding to the highest of the depressed keys, separate means for dividing the frequencies of the signals produced by said oscillators to produce sub-multiple frequency signals, and tone control circuits for coupling said last named means to the output system.

6. In an electrical musical instrument, means for dividing the frequency of a source of constant amplitude electrical impulses comprising, a rectifier, reactive means coupling said rectifier to the source of impulses, a charge storing condenser coupled to said rectifier to receive the output thereof, and relaxation means effective to discharge said condenser whenever the potential across said condenser exceeds a predetermined value.

12

7. In an electrical musical instrument having an amplifying and electroacoustic translating system, the combination of a tunable variable frequency signal generating oscillator, a plurality of playing keys, means operated by said keys to vary the tuning of said oscillator and to cause it to oscillate at a frequency related to an operated key, a pair of similar electron discharge devices, each comprising an input and a plate circuit, and cathode, grid and plate electrodes, means intercoupling the plates and grids of said devices, means for coupling the output of said oscillator to the input circuits of both of said devices, said couplings between the plates and grids of said devices being arranged to cause voltages on said electrodes of value to materially reduce plate current flow in one of said devices upon an increase in the flow of plate current in the other of said devices and vice versa, whereby said devices will alternately be rendered of increased conductivity upon receiving successive signal impulses from said oscillator and produce a wave in the plate circuits of each of said devices comprising substantially solely a fundamental of one-half the frequency of said oscillator and a musically desirable series of odd harmonics of said fundamental frequency, and means for selectively coupling one of said devices or said oscillator, or both, to the amplifying and electroacoustic translating system.
